UNITED STATES PATENT OFFICE

SHAFTER N. DUNBAR, OF WESTBURY, NEW YORK

FLOATAGE

Application filed September 12, 1930. Serial No. 481,485.

This invention relates generally to devices for maintaining a disabled ship against sinking, and which may be also employed to raise a ship which is sunk in the water. The invention specifically relates to an inflatable structure, which when deflated is carried on board the ship and is adapted to be thrown overboard in time of danger of sinking, and inflated, so that it will bear the weight of a ship and cargo, and maintain them against sinking in the water.

It is an object of this invention to provide a new and novel structure of this type, which is extraordinarily effective and convenient to use, and which may be installed upon and carried by ships and water vehicles of various types, with slight modifications.

The above and new and novel arrangement and combination of parts as will be herein-after more clearly perceived.

It is also an object of this invention to provide a device of the character described which comprises a plurality of inflatable structures arranged to expand and to be suspended from the outside and completely around the ship, and which may be taken on board the ship when not in use quickly and easily and placed into operative position in an emergency.

It is also an object of the invention to provide a device of the character described, which comprises a plurality of air chambers, secured to and suspended from the ship in a novel manner for sustaining the ship in an emergency.

It is also an object of this invention to provide a superior and successful device of the character described which is adapted to be inflated by pumps in a manual or mechanical operation, which are connected to the inflatable chambers by means of compressed air conduits that may be quickly and expeditiously filled with air in an emergency to support the ship against sinking in the water and becoming lost.

These and other objects of the invention, its nature and its composition and arrangement and combination of parts, will be readily understood from a reading of the following description from the drawings in which:

Figure 1 is a side elevational view of a ship showing the manner of installation of my improved floatage thereon,

Figure 2 is a top view of Figure 1,

Figure 3 is an end view partly in cross section showing the disposition of the floatage at the side and one end of the ship, and

Figure 4 is a transverse vertical cross section through one of the floats or air chambers disclosing the formation thereof.

It is to be definitely understood that I do not desire to limit the application of this invention to the particular modification set forth herein to illustrate the principle thereof, and any change or changes may be made in material or structure consistent with the spirit and scope of the invention.

Referring in detail to the drawings, the numeral 5 designates generally a ship having the floatage generally designated 6 suspended and secured thereabout and very clearly indicated in Figures 2 and 3. Floatage 6 consists of a plurality of inflatable floats 7 which are secured in end to end relation about the ship. The formation of said floats can be quickly and accurately described and understood by reference to Figure 4 which the numeral 8 indicates an interior rubber or rubber composition bladder and has surrounding it in various directions a heavy canvas band 9, and the numeral 10 denotes a sheath of heavy rope netting. It is obvious that this construction forms a very strong and durable structure, capable of standing up under the most adverse circumstances met with weather at sea. The object of providing a plurality of the floats 7 is that the puncture of them or a few of them will not affect materially the supporting power of the remaining floats, whereas the provision of a single, communicating structure would result in disaster should it be punctured or otherwise injured dooming the vessel to become lost to the mercies of storm passed waters. The numeral 11 denotes heavy canvas reinforced bands which are constructed to go about the floatage and under the ship, for maintaining the said floatage and the said ship in proper relation for preventing the undue separation of either

side of the floatage from the companion side of the ship. The bands 11 have their ends wrapped around portions of the floatage and chains 12 are connected with said bands at their juncture with the said floatage, the upper ends of the chains 12 being connected with the ship. Figure 3 indicates the proper suspension angle as permitted by the provision of the said chains which are attached near the upper part of the hull of the vessel as indicated at 13. Of course suitable means for affixing this attachment may be employed, so long as they conform to the principles laid down herein.

15 Provision is made for individually inflating floats or groups of floats or in like manner deflating the floats of said floatage. This provision consists in a plurality of flexible pipes 14 which lead from the pumping station on board the ship to the various floats or as indicated in the drawings. As stated, the entire structure of the floatage is adapted to be hoisted on board the ship when not in use and in deflated condition and stored 20 in the same manner as lifeboats and the like now maintained, and it is a simple and expeditious movement and maneuver, with suitable mountings, to project the device overboard in an emergency and to inflate the 25 same either while it is in process of being placed overboard or while it is disposed in 30 said position.

The time required for inflating is not so excessive as to require very high powered 35 pumps and the inflation may be accomplished by hand pumps, should the power pump be disabled through any cause, the usual delay between the occurrence of an emergency and the danger point is usually sufficient to enable the float to be inflated manually to effectively sustain the ship against the threatened sinking.

It is thought to be obvious that I have provided a device of the character described and 40 effective in operation, is not expensive to manufacture or to install, which comprises new and novel features which indicate a construction of high efficiency and great power and usefulness in emergency and which may 45 be adapted to similar and other maritime emergencies, and which is otherwise admirably adapted for the purpose for which it is designed.

Having thus described my invention, what 50 I claim as new is:

Means for preventing a disabled ship from 55 sinking, comprising a buoyant member entirely surrounding the ship and composed 60 of a plurality of cylindrical tubular members, each formed of resilient material, means for inflating said members, an outer tubular covering formed of netting for receiving the 65 cylindrical members and holding them in end to end relation, strips of flexible material hav-

ing their ends connected with the sides of the buoyant member and passing under the ship, a longitudinally extending flexible member having its ends connected with the ends of the buoyant member and passing under the ship, and flexible members for connecting the side portions of the buoyant member with the sides of a ship.

In testimony whereof I affix my signature.

SHAFTER N. DUNBAR.
